UNITED STATES PATENT OFFICE.

PAUL SABO, OF RACINE, WISCONSIN.

SLIDING-JAW WRENCH.

1,111,616.

Specification of Letters Patent. Patented Sept. 22, 1914.

Application filed December 29, 1913. Serial No. 809,815.

To all whom it may concern:

Be it known that I, PAUL SABO, a citizen of the United States of America, residing at Racine, in the county of Racine and State of Wisconsin, have invented certain new and useful Improvements in Sliding-Jaw Wrenches, of which the following is a specification, reference being had therein to the accompanying drawing.

10 This invention relates to sliding jaw wrenches, and has for its object to provide a wrench of that class, in a manner as hereinafter set forth, with means for maintaining the sliding jaw in the position to which it has been adjusted, said means being further capable of being conveniently released to enable the sliding jaw to be quickly shifted when occasion so requires.

20 Further objects of the invention are to provide a sliding jaw wrench, which is comparatively simple in its construction and arrangement, strong, durable, efficient and convenient in its use, readily adjusted and comparatively inexpensive to manufacture.

25 With the foregoing and other objects in view, the invention consists of the novel construction, combination and arrangement of parts as hereinafter more specifically described and illustrated in the accompanying drawings, wherein is shown an embodiment of the invention, but it is to be understood that changes, variations and modifications can be resorted to which come within the scope of the claims hereunto appended.

30 In the drawings wherein like reference characters denote corresponding parts throughout the several views:—Figure 1 is an elevation of a sliding jaw wrench in accordance with this invention, Fig. 2 is a sectional side elevation broken away, Fig. 3 is a sectional front elevation broken away, Fig. 4 is a side elevation broken away, partly in section and with one of the elements of the sliding jaw removed, and Fig. 5 is a side elevation broken away.

35 Referring to the drawings, 6 denotes a shank which is oblong in cross section and which has its front edge, intermediate its ends formed with transverse teeth 7. Fixed 40 to the outer end of the shank 6 is a jaw 8, said shank 6 being connected to said jaw 8 centrally with respect thereto. Mounted upon the inner portion of the shank 6 is a handle 9, the latter being positioned inwardly with respect to the teeth 7.

The reference character 10 denotes a slid-

ing jaw which is formed centrally thereof with an opening 11 for the passage of the shank 6. Formed integral with the front of the jaw 10 at the inner terminus thereof is a rearward extension 12 having integral therewith a transversely extending semi-cylindrical block 13 of a length greater than the width of the extension 12. The block 13 at its inner portion has a rearwardly extending flange 14 of the same width as the width of the extension 12. The block 13 centrally thereof, is provided with a chamber 15 opening toward the shank 6 as at 16, and said block 13 at one side is provided with a stepped pocket 17, closed through the medium of a plate 18, mounted in the larger portion of said pocket 17. Journaled in the block 13 is a shaft 19 which is disposed transversely with respect to the shank 6, and extends through the chamber 15 and into a portion of smaller diameter of the pocket 17. Fixed to the shaft 19 so as to rotate therewith, and arranged within the chamber 15 is a toothed wheel 20, which engages with the teeth 7 and constitutes a retaining means to prevent the shifting of the slideable jaw body and shank when said shaft 19 is locked from movement.

45 Associated with the shaft 19 is a locking device therefor which consists of a toothed disk 21 arranged within the smaller portion of the pocket 17 and fixed to the shaft 19. Journaled in a recess 22, formed in the block 13, and opening into the pocket 17, is a locking member 23, which has a reduced cylindrical portion 24 journaled in the disk 16. The locking member 23 is furthermore provided with a semi-cylindrical portion 25 which opposes the disk 21. The outer end of the locking member 23 has a head 26. The reduced cylindrical portion 24 of the locking member 23 provides a pair of shoulders 27, 28, which when said locking member is in position prevents longitudinal movement of said member. The wall of the pocket 17 is formed with a groove 29 in which is seated said locking member.

50 Projecting rearwardly from the jaw 10 are longitudinally disposed straps 30, which are formed integral with the block 13 and also with the flange 14 and are connected together by a transverse strap 30, which extends across the rear edge of the shank 6. 110 When the semi-cylindrical portion 25 of the locking member 23 extends into the disk 21,

between the teeth 31 of said disk 21, the shaft 19 is locked from movement whereby the toothed wheel 20 cannot rotate and owing to the fact that the teeth of the wheel 20 engage in the teeth 7 of the shank 6, the sliding jaw 10 is arrested from movement. By shifting the member 23 to move the semi-cylindrical portion 25 clear of the disk 21, the shaft 19 is free to rotate whereby the jaw 10 can be shifted to the position desired upon the shank 6.

What I claim is:—

- 15 1. A wrench comprising a toothed shank having a fixed jaw, a sliding jaw body adjustable upon said shank, a shaft rotatably mounted in said body, a toothed wheel carried by the shaft and permanently engaging the teeth of the shank, a toothed disk fixed to the shaft, and a rotatable locking member carried by said jaw body and having a semi-cylindrical portion capable of extending into said disk for locking the same when said member is shifted thereby preventing
- 20

rotation of said shaft and locking jaw body in the position to which it has been adjusted. 25

2. A wrench comprising a toothed shank having a fixed jaw, a sliding jaw body adjustable upon said shank, a shaft rotatably mounted in said body, a toothed wheel carried by the shaft and permanently engaging the teeth of the shank, a toothed disk fixed to the shaft, a rotatable locking member carried by said jaw body and having a semi-cylindrical portion capable of extending 30 into said disk for locking the same when said member is shifted thereby preventing rotation of said shaft and locking the jaw body in the position to which it has been adjusted, and means to prevent longitudinal movement of said locking member. 40

In testimony whereof I affix my signature in the presence of two witnesses.

PAUL SABO.
